[57] ABSTRACT

A pipe having a series of receptacles coupled to a common stem and adapted to accommodate separate charges of tobacco. A common lid covers all of the receptacles and is displaceable to permit the insertion of tobacco. The lid is provided with draft openings over the respective receptacles, there being individually controllable covers associated with the openings to allow a draft to be drawn through one receptacle at a time. A tobacco lighting device may be incorporated into the pipe construction.

PIPE WITH A PLURALITY OF RECEPTACLES

FIELD OF THE INVENTION

This invention relates to pipes for the smoking of tobacco and the like, and more particularly to pipes provided with novel bowl arrangements.

BACKGROUND

Conventional pipes are known which are provided with a single bowl or receptacle into which tobacco is loaded for smoking. This tobacco is smoked continuously or intermittently to completion whereafter the bowl is cleaned and recharged so that the pipe can be smoked again.

The pipe owner usually carries a supply of tobacco with him thereby enabling him to refill his pipe. This represents a great inconvenience which it is desirable to avoid since tobacco pouches or other such packages are generally bulky and difficult to store.

Additionally, the smoking of a pipe load ordinarily requires a substantial period of time. This makes pipe smoking impractical under a wide variety of circumstances. To accommodate such circumstances, pipe smoking is sometimes practiced by the partial smoking of a pipe load, letting the tobacco go out and then re-lighting the tobacco at a later time. This cycle can be repeated. However, it has been found that the retaining of a partly smoked tobacco charge in a pipe can be both dirty and dangerous as charred tobacco remains and glowing embers can be spilled onto furniture and clothing to soil and burn the same.

SUMMARY OF THE INVENTION

It is an object of the invention to provide an improved pipe having a plurality of receptacles.

It is another object of the invention to provide an improved pipe adapted for carrying a plurality of independent tobacco charges and of a construction which enables the pipe user to smoke individual tobacco charges one at a time.

It is yet another object of the invention to provide for sequential smoking of tobacco charges independently of one another in a manner which avoids dirty and dangerous conditions which usually result from the intermittent smoking of tobacco charges.

To achieve the above and other objects of the invention, there is provided in accordance therewith a pipe which comprises first means defining a plurality of receptacles adapted for accommodating individual charges of tobacco, a stem coupled to these receptacles and adapted to draw smoke from tobacco burning in the same, and second means associated with said receptacles and adapted for controlling the receptacles to allow a draft to be drawn selectively through the receptacles into and through the stem in such manner that one receptacle can be used to the exclusion of the others.

In the aforesaid generalization, the second means may include a lid which is common to all of the receptacles and which is provided with openings respectively aligned with the receptacles, there being provided individual covers on the lid controllably covering respective of the openings.

According to respective features of the invention, the above-mentioned lid may be pivoted to the first means or hingeably connected thereto. According to a more specific feature of the invention, the above-noted first

means may include an elongated body in which the receptacles are rectilinearly and consecutively aligned. Optionally, the pipe of the invention may include means for individually lighting tobacco charges in the respective receptacles.

The above and further objects, features and advantages of the invention will be found in the detailed description which follows taken in conjunction with the accompanying drawing.

BRIEF DESCRIPTION OF THE DRAWING

In the drawing:

FIG. 1 is an exploded perspective view of a pipe provided with a plurality of receptacles in accordance with a first embodiment of the invention and including a tobacco lighting means thereon;

FIG. 2 is a sectional view through the pipe of FIG. 1 with the lid of the pipe closed, the view being taken generally along the section indicated by line II-II;

FIG. 3 illustrates diagrammatically but in greater detail in perspective, a lighting device which can be employed in the embodiment of FIG. 1;

FIG. 4 is an exploded view similar to FIG. 3, of another lighting device which can be employed in the construction of FIG. 1, with parts broken away; and

FIG. 5 is a perspective view of a further embodiment of the invention.

DETAILED DESCRIPTION

As stated hereinabove, the invention provides a pipe which comprises first means defining a plurality of receptacles adapted for accommodating individual charges of tobacco, there being a stem coupled to these receptacles and means for selectively enabling a draft to be drawn through respective of the receptacles.

In FIG. 1 there appears a pipe 10 including an elongated body 12 defining an internal chamber which is upwardly open and bounded by ends 14 and 16, the chamber being divided by partitions 18, 20, 22 and 24 into receptacles 26, 28, 30, 32 and 34. The receptacles are rectilinearly aligned in the illustrated embodiment and are consecutively arranged.

The elongated body 12 is provided with an end portion 36 to which is pivoted a lid 38 by means of a pin 40. The purpose and function of the lid is to allow the positioning of individual tobacco charges in the various receptacles while the lid is pivoted to open position as shown and to provide for the selective drawing of drafts through the respective receptacles when the lid is in closed position as generally shown in FIG. 2.

To enable the selective drawing of drafts through the various receptacles, the lid 38 is provided with holes or openings 42, 44, 46, 48 and 50, these openings being aligned with the various receptacles when the lid is pivoted to closed position.

Associated with the aforesaid openings 42-50 are pivotable covers 52, 54, 56, 58 and 60, these being pivoted to lid 38 by pins such as indicated at 62 and being pivotable between open positions, as illustrated in FIG. 1, and closed positions in which they obturate the corresponding openings.

As appears in FIG. 2, each of the receptacles such as, for example, the receptacle 30 is laterally bounded by walls 64 and 66 of the elongated body 12 and by a floor 68, which is also a part of the elongated body 12. The individual charge of tobacco is indicated at 70 and may be a charge of loose tobacco or a charge of a preformed

pellet or the like which may be formed by conventional techniques.

To the floor 68 is attached a pipe stem 72 which extends longitudinally along the entire length of the elongated body 12. Through the stem 72 extends a longitudinal bore 74 which is connected to the respective receptacles by means of independent bores or risers 76. It will be appreciated that, although the stem 72 is shown in monolithic arrangement with the elongated body 12, it is possible that these two components be separately fabricated and attached by any means whatsoever. It is also apparent that the structure which has been described to this point may be fabricated of briar, ceramic or other such materials as are conventional in the construction of pipes.

Also appearing in FIG. 1 is a bit 80 having an extension 82 which extends into the bore 74 in the stem 72. A frictional fit is possible to join the bit with the stem but a threaded connection is also possible according to known techniques. The bit 80 may be formed of rubber or plastic or other such materials as are customary in conventional pipe construction.

From what has been stated hereinabove, it will be understood that individual tobacco charges may be loaded into the individual receptacles with the lid 38 pivoted to open position. Thereafter the lid 38 will be pivoted to closed position. With all of the covers 52-60 obturating the associated openings 42-50, no draft can be drawn through any of the receptacles into the bore 74 and outwardly through the bore which is provided in the bit 80. However, it is now possible to pivot any one of the covers 52-60 to open position whereby a draft may be drawn through the corresponding receptacle through the corresponding riser 76 and into the bore 74 and thence through the bit 80 to allow the smoking of the tobacco in the selected receptacle.

The openings 42-50 are made sufficiently large so that a lighting of the tobacco may be effected therethrough. Such lighting may be provided for by the use of a lighting mechanism indicated diagrammatically and generally at 86, the lighting device 86 being affixable to the end 14 of the elongated body 12 by means, for example, of prongs 88 and 90 or by magnetic means or bayonet connections or by any other suitable connection whatsoever.

FIGS. 3 and 4 illustrate that the lighter may be of the electrical type or of the fuel type. In FIG. 3, for example, there is diagrammatically illustrated a lighter 92 which may be employed in connection with the foregoing construction. On this lighter is provided an exposed and projecting filament 94 electrically actuated by means of a rechargeable battery concealed within the body of the lighter and charged by means of the electrical prongs 96 and 98. FIG. 4 illustrates a fuel type lighter in which the body 100 is provided with an opening 102 for the insertion of fuel which is absorbed in an internally arranged cotton wad 104, there being furthermore provided an opening 106 in which is accommodated a striker 108. This construction is known and conventionally includes a striking strip 110 which coacts with the tip 112 of the striker 108 to provide a flame. Either this flame or the aforesaid filament 94 or individual matches or lighters may be employed to ignite the tobacco charge in the selected one of the afore-mentioned receptacles.

FIG. 5 illustrates a further embodiment of the invention in which an elongated body 120 is provided with

a plurality of receptacles 122, 124, 126, 128 and 130, these receptacles being separated by intervening partitions. As in the aforesaid embodiment, the elongated body 120 has associated therewith a stem 132 through which extends a bore 134.

In this embodiment of the invention, a lid 136 is hingeably connected to the elongated body 120 by a hinge device 138 of conventional construction allowing the lid 136 to be pivoted between open and closed positions.

The lid 136 is provided with a plurality of openings corresponding to respective of the receptacles mentioned above, each of the openings being provided with a hinged cover 140 which allows the selective actuation 15 of one of the receptacles comprised within the elongated body 120.

The embodiment of the invention illustrated in FIG. 5 is furthermore provided with a bit in the manner described above and may also and optionally be provided 20 with a lighting mechanism especially adapted for use in connection with the openings.

From what has been described hereinabove, it will now be understood that there is provided, in accordance with the invention, a pipe comprising first means defining a plurality of receptacles adapted for accommodating individual charges of tobacco, a stem coupled to these receptacles and adapted to draw smoke from tobacco burning in the same, and second means associated with the receptacles and adapted for controlling the receptacles to allow a draft to be drawn selectively through the receptacles into and through the aforesaid stem. It will be readily appreciated that the means for selectively actuating one receptacle at a time may be physically located other than in superposition to the respective receptacles and, for example, it is possible to provide an obturating means in association with the risers 76 illustrated in FIG. 2.

The illustrated embodiments, however, include lids common to all of the aforementioned receptacles and 40 provided with openings respectively aligned with the receptacles, there being furthermore provided individual covers on the lids controllably covering respective of the openings so that, for example, only one opening need be open at a given time. It will of course be appreciated that the pipe smoker may at his option smoke 45 two receptacles at a time in which case parallel drafts will be drawn into the pipe stem.

There will now be obvious to those skilled in the art many modifications and variations of the constructions 50 set forth above. These modifications and variations will not depart from the scope of the invention if defined by the following claims. Thus, for example, it will now be obvious that each of a plurality of receptacles provided in accordance with the invention may be provided with its own separate cover which permits separate charging and separate smoking, these receptacles all being coupled to a common manifold.

What is claimed is:

1. A pipe comprising a first means defining a plurality of receptacles adapted for accommodating individual charges of tobacco, a stem coupled to said receptacles and adapted to draw smoke from tobacco burning in the same, and second means associated with said receptacles and adapted for controlling the receptacles to allow a draft to be drawn selectively through the receptacles into and through said stem, said second means being effective to allow a draft to be drawn through one

receptacle at a time and including a lid common to all of the receptacles and provided with openings respectively aligned with said receptacles, and individual covers on said lid controllably covering respective of said openings.

2. A pipe as claimed in claim 1 wherein said lid is pivoted to said first means.

3. A pipe as claimed in claim 1 wherein said lid is

hingeably connected to said first means.

4. A pipe as claimed in claim 1 wherein said first means includes an elongated body in which the receptacles are rectilinearly and consecutively aligned.

5. A pipe as claimed in claim 1 comprising means on said first means for individually lighting tobacco in the individual receptacles.
